LEWIS Y. KETCHAM AND JAMES TAYNTON, OF PORT JERVIS, NEW YORK.

Letters Patent No. 99,912, dated February 15, 1870.

IMPROVEMENT IN YARD AND TANK-CRANES.

The Schedule referred to in these Letters Patent and making part of the same.

To all whom it may concern:

Be it known that we, LEWIS Y. KETCHAM and JAMES TAYNTON, of Port Jervis, in the county of Orange, and State of New York, have invented a certain new and useful Improvement in Water-Cranes for Feeding Locomotives, of which the following is a specification; and the following is a full, clear, and exact description of the same, reference being had to the accompanying drawings making a part of this specification, in which—

Figure 1 represents a side elevation of the underground portion of apparatus to which the crane is attached.

Figure 2 shows a section through the balanced supply-valve.

Figure 3 shows a sectional view of the waste or outlet-valve.

Our invention is an improvement on the water-crane patented to LEWIS Y. KETCHAM, February 12, 1867, and consists in the application of a double cone-seated balance-valve, as arranged and connected with the water-crane and the supply-pipe, so as to be operated with the greatest ease under any pressure of water.

Also, in the construction and arrangement of the waste or outlet-valve, and the lever connections for operating the same.

To enable others to make and use our improvements, we will describe them more fully, referring to the drawings and letters marked thereon.

The joint A is connected with the supply-pipe, and provided with an air-chamber, B, as shown in fig. 1.

The joint C is provided with a cone-seated balance-valve, *a b*, and vertical rod, *c*, as shown in fig. 2, connecting with the lever H for operating the same.

The joint D is cast with and supported on the base E or standard of the crane.

The waste-valve *d*, as seen in fig. 3, is attached to the lower portion of the bulb of the joint D, and is so arranged that when the valve *a b* is opened the force of the water closes it, and when the water is shut off from the crane, the connecting-link *f* attached to the slide *h* operated by the lever H, presses upon the stem of the waste-valve *d*, causing it to open, thus allowing the water to escape quickly from the upper portion of the crane.

What we claim as our invention, and desire to secure by Letters Patent, (as an improvement on the patent aforesaid,) is—

The arrangement and combination of the balanced valves *a b* and waste-valve *d* with their connecting apparatus, consisting of rods *e* and *c* and lever H, substantially as herein described.

In testimony whereof we hereunto subscribe our names.

LEWIS Y. KETCHAM.

JAMES TAYNTON.

GEORGE BRODHEAD,
GEO. CLAWSON.
